UNITED STATES PATENT OFFICE.

JOHN WILLIAM SUTCLIFFE AND HARRY SUTCLIFFE, OF LONDON, ENGLAND.

SHIRT-IRONING MACHINE.

SPECIFICATION forming part of Letters Patent No. 634,376, dated October 3, 1899.

Application filed February 21, 1898. Serial No. 671,157. (No model.)

To all whom it may concern:

Be it known that we, JOHN WILLIAM SUTCLIFFE and HARRY SUTCLIFFE, subjects of the Queen of Great Britain and Ireland, residing at 26^a Theberton street, Upper street, Islington, London, England, have invented certain new and useful Improvements in or Relating to Shirt-Ironing Machines; and we do hereby declare the following to be a full, clear, and exact description of the invention, such as will enable others skilled in the art to which it appertains to make and use the same.

This invention relates to those shirt-ironing machines having a sliding or moving table which runs beneath a heated revolving roller or fixed iron or other suitable ironing agent.

The object of the invention is to prevent as far as practicable waste of time and heat of the ironing-rolls while the operator is arranging the shirt-bosom upon the ironing-board. This is accomplished by providing means for utilizing the operation of the machine and the heating agent in a practically continuous manner.

Reference is had to the accompanying drawings, in which the same parts are designated by the same letters of reference throughout the several views.

Figure 1 is a front elevation of the upper portion of a shirt-ironing machine constructed in accordance with our invention. Fig. 2 is a detached plan, on a somewhat larger scale, of the sliding table. Fig. 3 is a plan, also on an enlarged scale, of the shirt-board. Fig. 4 is a plan, on a similar enlarged scale, of the sliding table with the shirt-board in position thereon. Fig. 5 is a plan of the same with a shirt in position thereon ready for ironing the shirt and cuffs simultaneously. Fig. 6 is a similar view with the shirt in position for ironing the cuffs only upon the shirt-board, the cuff-blocks being dispensed with. Fig. 7 is a central longitudinal sectional view, on an enlarged scale, through the shirt-board and the supporting-board, showing them in position for use. Fig. 8 is a detail perspective view, on an enlarged scale, showing one of the cuff-blocks and one of the clamps for holding the sleeves of the shirt against the said block.

c designates the heated ironing-roller, which

is journaled in the frame of the machine and may be heated and turned by any suitable means.

f designates the sliding table, which is arranged to slide beneath the said roller and has a board *a* secured upon its upper side, this board being provided with an upwardly-projecting strip *b* at one end thereof, against which the shirt-board *g* (shown in Fig. 3) is adapted to rest.

The shirt-board *g* is provided with the ordinary stretching-roller *k* and pawl-and-ratchet device *l* for holding the same.

Upon the top of the sliding table *f*, on each side of the board *a*, are secured the cuff-blocks *d* and *e*, the spring-clamps *h* being arranged to hold the part of the sleeves adjacent to the cuff against the sides of the said cuff-blocks, and so hold the cuffs upon the blocks in position for ironing. By this device the shirt-bosom may be placed upon the shirt-board and the cuffs upon the cuff-blocks all in position for ironing simultaneously.

Should the cuff-blocks not be used, as shown in Fig. 6, the cuffs may be placed upon the shirt-board *g* and ironed separately.

According to our invention, instead of the usual block shaped in conformity to the shirt-bosom, we fix three platforms or blocks, as shown in Fig. 2, which may be of any suitable material and shape and placed in any suitable position; but preferably we place them in the position shown on the drawings.

The projecting strip *b*, fixed to the edge of the platform or block *a*, is parallel to the revolving roller *k*. The shirt-board *g* is placed on the platform or block *a*, as shown in Figs. 4 and 7, the strip *b* determining its position. The platforms or blocks *d* and *e* are for the cuffs. The center platform *a* is made of such a thickness that when a shirt-board *g* is placed upon it the upper surface of such board is exactly level with the two blocks *d* and *e*. (See Fig. 1.) On these two cuff-blocks *d* and *e* we place felt or padding of any suitable material, and we make this easily removable in order that it can be changed when damp without serious loss of time. We also cover the shirt-boards *g* with felt or other suitable material.

We may use a number of the shirt-boards *g*.

The mode of operation is as follows: A shirt is placed upon the shirt-board *g* so that the bosom lies upon the padded side. The said board is then placed upon the platform *a* so that the back of the shirt rests between the surface of the platform *a* and the under side of the shirt-board *g*. The operator is able to put the shirt-board *g* exactly square upon the platform *a*, as the skirt end of the shirt-board rests against the strip *b*, as shown at Figs. 4 and 7. The operator then places the cuffs upon the blocks *d* and *e*, using the clamps *h*, Figs. 2 and 4, to hold them in position. (Shown at Fig. 5.) The shirt-bosom and cuffs are now ready to be ironed, and the operator manipulating the machine runs the sliding table *f* under the revolving roller *c*, thus ironing the bosom and cuffs of the shirt simultaneously. While the operator is working the machine an attendant can arrange shirts upon other shirt-boards *g*. Thus when the first shirt is finished another shirt-board *g* is always ready for the operator and no time is wasted.

25 The advantages of having several shirt-boards which can be easily changed without loss of time will be obvious to those skilled in the art to which the invention appertains.

We would draw special attention to the fact that on our improved principle the shirt-board *g* is not attached to the platform *a* in any way, and when the sliding table is run under the heated roller this shirt-board does not slip or shift from its position on the platform *a*, but remains in the same position as placed by the operator, and, further, it does not require holding in any way, thus leaving the operator's hands free, and therefore he or she is better able to attend to the ironing 40 without running any risk of being caught under the ironing-roller.

If it should be desired to iron the bosom of the shirt in one operation and the cuffs in a separate operation, we make the sliding table *f* as shown in Fig. 6, in which case we use the platform *a* without the blocks *d* and *e*, but with the shirt-board *g*. After the shirt-bosom has been ironed the cuffs can be ironed by removing the shirt-bosom from the 45 shirt-board and placing the cuffs on this board and again placing it upon the platform *a* and ironing, as before described.

50 Although we have described the blocks for the cuffs as used in combination with our removable shirt-board *g*, it is obvious that they may be used on the ordinary platform, which carries a fixed shirt-board.

55 As our invention refers to the sliding table, we do not require to make a special machine,

but may use the same machines as at present 60 in use with sliding tables.

What we claim as our invention, and desire to secure by Letters Patent, is—

1. In an ironing-machine, the combination with a sliding table, a fixed platform thereon 65 for a shirt-board, and a pair of cuff-blocks secured upon opposite sides of said platform to said sliding table, substantially as described.

2. In an ironing-machine, the combination 70 with an ironing-roll, of a sliding table, a pair of cuff-blocks secured upon said sliding table, and clamps secured upon the sliding table and bearing against the said cuff-blocks for securing the cuffs in position upon said 75 blocks, substantially as described.

3. In an ironing-machine, the combination 80 of a sliding table, a fixed platform thereon, a shirt-board detachably held on said platform, and cuff-blocks secured to said table, substantially as described.

4. In an ironing-machine, the combination 85 of a sliding table, cuff-blocks thereon, a platform provided with a projecting strip at one end also secured to said table, said platform 90 being on a lower level than said blocks, and a shirt-board adapted to rest on said platform and against said strip, substantially as described.

5. In an ironing-machine, the combination 90 of a sliding table, cuff-blocks and a platform thereon, and a shirt-board provided with a ratchet-and-pawl mechanism for firmly holding a shirt on said board, said board being detachably held on said platform, substantially 95 as described.

6. In an ironing-machine, the combination 100 of a sliding table provided with cuff-blocks and a platform, clamps for holding the article to be ironed in engagement with said blocks and a shirt-board detachably held on 105 said platform, substantially as described.

7. In an ironing-machine, the combination 110 with an iron, means for heating and rotating said iron, and a sliding table, of cuff-blocks secured to said table, clamps coöperating with said blocks, a platform secured to said table and provided with a projecting strip at one end, and a shirt-board provided with means for securely holding a shirt thereon, 115 said board being designed to rest on said platform with one end against the projecting strip thereon, substantially as described.
